(57) **CLAIM**

The ornamental design for a gyroscope, as shown and described.

DESCRIPTION

FIG. 1 is a perspective view of the first embodiment of the gyroscope.

FIG. 2 is a front elevation view of the first embodiment of the gyroscope.

FIG. 3 is a back elevation view of the first embodiment of the gyroscope.

FIG. 4 is a left elevation view of the first embodiment of the gyroscope.

FIG. 5 is a right elevation view of the first embodiment of the gyroscope.

FIG. 6 is a top plan view of the first embodiment of the gyroscope.

FIG. 7 is a bottom plan view of the first embodiment of the gyroscope.

FIG. 8 is a perspective view of a second embodiment of the gyroscope.

FIG. 9 is a front elevation view of the second embodiment of the gyroscope.

FIG. 10 is a back elevation view of the second embodiment of the gyroscope.

FIG. 11 is a left elevation view of the second embodiment of the gyroscope.

FIG. 12 is a right elevation view of the second embodiment of the gyroscope.

FIG. 13 is a top plan view of the second embodiment of the gyroscope; and,

FIG. 14 is a bottom plan view of the second embodiment of the gyroscope.

The broken lines in the drawings illustrate subject matter which forms no part of the claimed design.
